United States Patent Office

Des. 211,980
Patented Aug. 20, 1963

211,980

BUILDING OR THE LIKE

Bailey C. Williams, 1200 Marlboro Road,
Raleigh, N.C. 27610

Filed Aug. 12, 1966, Ser. No. 3,442

Term of patent 14 years

(Cl. D13—1)

Hg 1

Hg 2

FIG. 1 is a perspective of a building or the like, showing my new design; and

FIG. 2. is a rear elevational view of such design.

The end of the building opposite that shown in FIG. 1 and the end shown in FIG. 1 are substantially identical.
I claim:

The ornamental design for a building or the like, as shown and described.
